UNITED STATES PATENT OFFICE

BAZEL E. CARRM, OF CHICAGO, ILLINOIS

DESIGN FOR A LAMP

Application filed August 6, 1931. Serial No. 40,792. Term of patent 7 years.

To all whom it may concern:

Be it known that I, BAZEL E. CARRM, a citizen of Argentina, residing at Chicago, in the county of Cook and State of Illinois, have invented a new, original, and ornamental Design for a Lamp, of which the following is a specification, reference being had to the accompanying drawings, in which Fig. 1 is a plan view of the article showing my new design; and Fig. 2 is an elevation thereof.

I claim:

The ornamental design for a lamp, as shown.

In testimony whereof I affix my signature.

BAZEL E. CARRM.
